CABINET IRONER

Alfred J. Shute, Chicago, Ill., assignor to Electric Household Utilities Corporation, Chicago, Ill., a corporation of Illinois

Application July 19, 1935, Serial No. 32,267

27 Claims. (Cl. 312—28)

My invention relates to improvements in ironers or ironing machines generally of the domestic type, and it has more particular reference to an improved structure in which the ironer is associated with a cabinet for containing the ironer when not in use.

One of the objects of my invention is to provide an ironer mechanism associated with a cabinet into which the ironer mechanism can be folded and completely enclosed when not in use and from which the ironer can be withdrawn and placed in operating position for use.

A further object of my invention is to provide a cabinet and ironer and mechanism in association therewith for supporting the ironer in either its closed position within the cabinet or in its open operating position outside the cabinet, and for supporting the ironer during its transition from its operating to enclosed position in such manner that very little physical effort is required on the part of the operator in moving the ironer into and out of the cabinet.

Other objects of my invention will appear from the specification and claims in conjunction with the accompanying drawings of mechanism in which the invention is embodied.

Referring to the drawings:

Fig. 1 is a front view of the cabinet with the ironer indicated therein in dotted lines;

Fig. 2 is an enlarged front view of the cabinet with the door open and the ironing machine extended therefrom in operating position;

Fig. 3 is a vertical section substantially on the line 3—3 of Fig. 2, showing the same position of the parts as illustrated in Fig. 2;

Fig. 4 is a vertical section similar to Fig. 3 but illustrating the ironer partially within the cabinet in the act of either being folded into the cabinet or withdrawn;

Fig. 5 is a similar sectional view to Figs. 3 and 4, except that the ironer is completely positioned within the cabinet;

Fig. 6 is an enlarged front elevation of the central portion of the structure shown in Fig. 2, with some of the details of the outboard leg operating mechanism shown in section, to better illustrate the relation of the various supporting and operating parts;

Fig. 7 is a detail section of the leg locking and safety mechanism shown in Fig. 6;

Figs. 8, 9 and 10 are enlarged detail views partly in section, of a modification of the outboard leg operating mechanism; and

Fig. 11 is a detail view of still another modi-

fication of the outboard leg operating mechanism.

The cabinet A in which the ironing mechanism is supported is of any suitable type for the purpose. It is preferably made of sheet metal rectangular in shape and sufficiently high to support and enclose within itself the ironing mechanism in an upright or vertical position. The cabinet has a suitable door 1 hinged at one side edge and adapted to swing outwardly to provide an opening through which the ironing mechanism is moved in transferring it from operating position to enclosed position or vice versa. The cabinet is preferably provided with casters 2 at its corners so that it can be moved about at convenience.

The ironer mechanism B is of the type generally known as domestic ironers and is a unit by itself in the sense that its parts are all related in such manner that it can be bodily swung out from the cabinet into operating position or vice versa.

In the present structure the ironer unit consists of an elongated baseboard 5 which is flat and substantially rectangular in shape and which is provided with an extension leaf 9 hinged along one edge and adapted to be folded on top of the baseboard when not in use. Adjacent one end this baseboard supports a head or standard 6 on which the ironer roll 7 and its cooperating ironing shoe 8 are mounted. These ironing elements of the ironer extend in parallel relation to the baseboard and are driven through suitable mechanism contained within the head 6 and which, so far as the present invention is concerned, need no further description.

Beneath the board at the end adjacent the head 6 and supported by the board is a suitable driving electric motor 10 and housing 11 which contains the driving connections between the motor and the head 6. These parts just referred to constitute the ironer unit. They are all permanently related to each other and to the baseboard so that the unit can be bodily moved into and out of the cabinet.

The cabinet has supporting mechanism on which this ironer unit is mounted and by which the ironer is supported and guided in its movement into and out of the cabinet. When the ironer unit is in operating position, it is wholly withdrawn from the cabinet and is disposed with the ironing roll, shoe and baseboard in horizontal position, as shown more clearly in Fig. 3. When the ironing unit is stored within the cabinet, as shown more clearly in Fig. 5, it occupies

a vertical position with the head and motor end uppermost. The structure is so arranged that the operator need only grasp the outer end of the unit and, with the exercise of very little physical effort, be able to swing the ironer outwardly to operating position or inwardly to storage position, as the case may be.

At its extreme end adjacent the head 6, the baseboard has upstanding arms or hangers 12 which carry flanged rollers 13 adapted to ride in guide channels or rails 14. One of these guide rails is mounted on each cabinet side wall. Their upper ends are fastened to and supported by brackets 15 and their lower ends are secured to horizontally disposed S-shaped members 16 mounted on the cabinet side walls. The lower forward end portions of these guide channels are horizontal and the rearward portions extend in a curve rearwardly and upwardly so that the ironer unit will be bodily rotated into a vertical position when moved into the cabinet and into a horizontal position when withdrawn from the cabinet. At the same time the head end of the unit is definitely supported by said channel members when in horizontal operating position. Adjacent the forward ends of the guide rails 14 are two vertical guide channels or rails 17, one on each side. The lower ends of the links 18 are guided by these rails 17 and are provided with rollers 18^a which engage the rails for this purpose. The upper ends of these vertical rails 17 are secured to the depending flange of the members 16 and the lower ends are secured to brackets 19 fastened to the wall of the cabinet. The upper end of the links 18 are pivotally connected to the ends of a transversely disposed strap member 20 secured to the under side of the baseboard about midway of the length thereof. As shown more clearly in Fig. 6, the end portions of the cross strap 20 are turned downwardly, then horizontally and then upwardly, to provide the vertical end portions 21 to which the ends of the links 18 are connected. The pivotal connection is formed by bolts 22 having flat heads on one end recessed in the ends of the links 18 and arranged to extend through the portions 21 and secured by collars 23 on their inner ends. The links 18 have offsets 24 about the center of their length so that the upper portions of the links are angularly disposed with respect to the lower portions. Another pair of links 25 are pivotally connected at their outer ends 26 to the links 18 and at their inner ends 27 to the upper ends of the vertical guides 17, the pivotal connections at the ends 27 of the links 25 being fixed against movement. The links 25 in conjunction with the links 18 suspend the weight of the ironer unit beyond the end supported by the connections with the channel rails 14 during the movements of the unit from one position to the other.

The ironing unit in its extended or operating position is supported by an outboard leg C which is arranged to automatically fold into a position substantially parallel with the ironer unit as the ironer is swung into the cabinet, and to automatically unfold and assume a supporting position as the ironer is swung out of the cabinet and into horizontal operating position. This supporting leg is positioned beneath the baseboard member of the ironer about midway of the length thereof and in general comprises two sections 30-31 which are hinged together. The upper section 30, as shown more clearly in Figs. 4 and 6, is in the nature of a bracket fas-

tened to the underside of the baseboard of the ironer about midway of the length thereof, and it has the latch mechanism associated with it. The lower section 31 is in the form of a tubular member having a suitable roller 31^a at its lower end. The section 30 has two downwardly extending arms 33 between which the upper end member 32 of the lower leg section 31 is positioned. The end member 32 is forked to provide two arms 34 and the hinge or pivotal connection is formed by two aligned shafts 35 secured to the arms 34 and journaled in bearings in the arms 33 of the upper section. The purpose in bifurcating the members 31 and 32 is to provide a space at the hinge joint for an operating cable 31^a for operating the control mechanism of the ironer unit. This cable extends downwardly through the hollow lower leg section 31 and connects with a suitable treadle 31^b.

One of the shafts 35 extends into a housing 36 supported by one of the arms 33 and carries a collar 37 fastened thereto and surrounded by a coil spring 38, one end 39 of which is secured to the arm 33 and the other end 40 of which is secured to a flange on the collar 37. This spring 38 is arranged to act upon the lower section 31 of the leg C in such manner as to tend to swing it into aligned or supporting position with respect to the upper section, so that as the ironer unit is swung to its operating position the spring will automatically swing the supporting leg section into position. One of the arms 34 has a lateral lug 42^a which engages the adjacent arm 33 and serves as a stop to prevent the lower section from being swung beyond aligned relation with the upper section of the leg. As the ironer unit is moved into the cabinet, however, the action of the spring is overcome by a bail member 41, hereinafter described, which folds the leg section 31 within the cabinet when the ironer reaches its position in the cabinet.

Locking mechanism is provided for locking the leg in its supporting position when the ironer unit is in horizontal position to prevent accidental folding of the leg. The locking action is brought about automatically in the movement of the unit. One of the arms 34 of the end member 32 carries a cam 42 having a notch 43 adapted to be entered by a latch pin 44 carried in the leg section 30 when the leg sections 30 are in aligned position. This latch pin is normally urged into engagement with the cam 42 by a coil spring 45. A release bar 46 is positioned horizontally in the section 30 and is reciprocable in suitable journals therein. This release bar has a tapered end 47 which is positioned (Fig. 6) in the path of movement of the upper portion of one of the links 18 and is normally urged outwardly by the coiled spring 48 positioned in a housing and acting on the end 47 of the release bar. A stop collar 49 limits the outward movement of the release bar to hold it in proper position. The release bar operates the latch pin 44 through a bell crank lever 50 with which both the latch member and release bar are pivotally connected. Thus as the link 18 passes the tip 47 of the release bar during the movement of the ironer, it acts as a cam to force the release bar inwardly, and this movement of the release bar acts to lift the latch member out of the notch 43.

The parts are so arranged that this action of the release bar occurs about the time the ironer unit is substantially half-way in the cabinet, as illustrated in Fig. 4, and a sufficient portion

of the weight of the ironer unit is in the cabinet, so that the center of gravity is within the confines of the cabinet and the weight of the ironer does not overbalance the structure.

- 5 About the time the unit reaches the position shown in Fig. 4, the bail 41 above referred to, engages the leg section 31 and folds the leg into parallel position with respect to the ironer in the final storage position within the cabinet.
- 10 The bail is comprised of two side members 51 connected by the cross bar 52 at their lower ends. The upper ends of these side members are pivoted at 53 to the flanges of the brackets 16 which are secured to the cabinet walls. The
- 15 lower portions of the side members 51 are turned forwardly at an angle so as to project the cross bar 52 into position to engage the lower section 31 of the leg C. A pair of springs 54, anchored to the brackets 16 and to the side members 51, urge the bail forward. These springs are sufficiently strong to overcome the spring 38 of the leg and fold the leg as the ironer goes into the cabinet. On the other hand, when the ironer is withdrawn from the cabinet, the spring actuated bail operates to keep the leg in folded condition until it is clear of the cabinet. Continued withdrawal of the ironer eventually carries the leg away from the bail and allows the spring of the leg to swing the lower section 31
- 20 into aligned supporting position.
- 25 30 A safety device is provided to maintain the leg in a supporting position in the event that some obstruction on the floor prevents the leg from unfolding during the movement of the ironer. This includes a notch 55 (Fig. 4) in the cam 42 positioned adjacent the locking notch 43 and arranged to be engaged by the latch pin 44. Normally the link 18 acting on the release bar 46 keeps the latch pin out of notch 55 until
- 35 the unfolding movement of the leg carries the notch 55 past the pin. If, however, some obstruction on the floor prevents the normal straightening out of the leg, the latch pin 44 will enter notch 55 as soon as the release bar is disengaged by link 18 and lock the leg against folding up in the event that the operator, after having fully withdrawn the unit from the cabinet, releases her hold on the unit and allows its weight to come upon the leg. Under this condition, if the leg were not locked, it would likely be folded by the weight of the unit, and the weight of the unit, being almost wholly outside the cabinet, would tend to overbalance the whole structure. When the operator discovers that the
- 40 45 50 55 60 leg is not in proper position, she simply moves the leg section 31 manually into alignment with section 30, or removes the obstruction and allows spring 38 to perform this function, in which event the edge of notch 55 acts to cam the latch pin 44 out of the safety notch.

In the bottom wall of the cabinet there is provided a stop 56 which is engaged by the outer end of the ironer baseboard to prevent the baseboard from being pushed too far into the cabinet.

- 65 Figs. 8, 9 and 10 illustrate a modified form of leg operating mechanism by means of which the leg section 31 is positively actuated to aligned position. In this form the upper end of the section 31 of the leg is hinged to the bracket or upper section 30 in a manner similar to that described in connection with the previous figures. The spring 38 and the collar 37 are positioned between the arms 33, instead of being in a separate housing outside of said arm. The
- 70 75 end 39 of the spring is anchored to the arm 33

and the end 40 of the spring is anchored directly to the arm 34 of end member 32 of the lower leg section. The link 18 has a cam member 60 secured to it at its upper pivotal end and the leg section 30 carries a shaft 61 which has a cam follower 62 at one end bearing upon the periphery of the cam 60. The cam follower is yieldingly maintained in contact with the cam by the spring 63 so that when the cam is rotated by the movement of the link 18 rotary movement will be imparted to the shaft 61. This shaft carries an arm 64 positioned between the members 33 of the bracket. The arm 64 has a laterally extending pin 65 which engages in a radial slot 66 in a member 67 which forms a part of one of the arms 34 so that the rotation of the shaft 61 will correspondingly rotate the leg section 31 through the medium of the arm 64 and the pin and slot connections 66 and 67. Since the action of the cam 60 on the mechanism is positive in the withdrawal movement of the ironer, the action of the spring 38 is overcome and the leg will be swung into aligned or supporting position. On the movement of the ironer to restore it to the cabinet, however, the spring 38 is relied upon to fold the leg.

Fig. 11 illustrates still another modified leg operating mechanism by which the leg is positively actuated in both directions of movement of the ironer unit and which accordingly is somewhat simpler in construction. In this form, the upper pivotal end of the link 18 is provided with a gear 68 which is rotated by the link. A toothed rack bar 69 meshes with this gear and is reciprocated longitudinally of itself in both directions by the rotation of the gear. The other end of the rack bar is pivotally connected at 70 to a crank arm 71 on a transverse shaft 72, this shaft being suitably journaled in brackets 13 secured to the underside of the baseboard of the ironer unit. In this modification, the leg C is not made in two sections, but instead is made as a single section, the upper end of which is secured to the shaft 72. Thus the rotation of the link 18 acts through the gear and rack bar to positively swing the leg C to folded or supporting position without the aid of any springs. The leg is folded toward the head end of the unit instead of away from it as in the previous forms. A U-shaped guard 75 forms a channel in which the rack bar 69 reciprocates, and this guard serves to hold the rack bar in mesh with the gear 68. This guard is preferably pivoted on the link 18 coaxially with the gear so that it may have some movement to adapt itself to the varying angular relation of the rack 69.

Assume that the parts are in the position shown in Fig. 3, with the ironer unit fully withdrawn from the cabinet and extending in horizontal position and supported by the leg C. In order to return the unit to its vertical position within the cabinet, the operator pushes longitudinally upon the ironer unit and causes the head end of the unit to move horizontally within the guide channels 14. At the same time the lower rollered ends of the links 18 move downwardly in the guide channels 17. The parts are so proportioned that the pivotal point 22 of the links 18 with the baseboard of the ironer unit travel in substantially a horizontal line throughout the entire movement of the unit into its cabinet. However, the rollered end 13 starts moving upwardly as soon as it reaches the beginning of the curved portion of the guide channels 14 and the outer end of the ironer unit 75

moves downwardly. The whole unit thus rotates about the pivotal points 22 and eventually assumes a vertical position within the cabinet. During the movement into the cabinet, and when the unit reaches about the position illustrated in Fig. 4, the leg C contacts the bail 41, the springs 54 of which are sufficiently stronger than the spring 37 of the leg to start folding the leg. At the same time the bail follows the movement of the whole unit into the cabinet until it eventually assumes the position shown in Fig. 5. In withdrawing the unit, the operator grasps the lower end of the baseboard and pulls outwardly thereon, whereupon the ironer unit will be bodily moved outwardly to its operating position and will be rotated into horizontal position during withdrawal.

I claim:

1. In a structure of the class described, the combination of a cabinet, an ironer unit including an ironing roll, a cooperating shoe and a base member, and supporting mechanism for said ironer unit connected with the cabinet and with said ironer unit and providing a movable pivotal support for said unit, said supporting mechanism being constructed and arranged for carrying and bodily moving the ironer unit downwardly about its pivot support into a vertical position within the cabinet or moving said unit to a horizontal position outside of the cabinet and maintaining said unit in horizontal position during its initial inward movement and final outward movement.

2. In a structure of the class described, the combination of a cabinet, an ironer unit including an ironing roll, a cooperating shoe and a base member, a supporting mechanism for said ironer unit connected with the cabinet and with the ironer unit for carrying said unit into a vertical position within the cabinet or a horizontal position outside of the cabinet, said mechanism including link members pivotally connected to the cabinet and said unit, and means for controlling the movement of said link members to guide the pivotal connection between the ironer unit and link members in a horizontal path, including guiding rails within the cabinet for rotating said ironer unit into either of its positions in its movement from one position to the other.

3. In a structure of the class described, the combination of a cabinet, an ironer unit including an ironing roll, a cooperating shoe and a base member, said unit being adapted to occupy a vertical position within the cabinet and a horizontal position exteriorly of the cabinet, means for supporting the ironer unit in its movement from one position to the other and bodily rotating the same into its vertical or horizontal positions, said means including pivot means on the inner end of said unit, supporting guide means on said cabinet on which said pivot means is slideable, and supporting guide links pivotally connected to the ironer unit and to the cabinet, the pivotal connection of said links with the ironer unit being outwardly of said pivot means.

4. In a structure of the class described, the combination of a cabinet having an opening in a vertical wall thereof, an ironing unit adapted to be moved into and out of the cabinet through said opening, said unit being arranged to occupy a vertical position within the cabinet and a horizontal position outside of the cabinet, a pair of links pivotally connected to the ironer and having a sliding connection with the cabinet, a second pair of links pivotally connected to the cabinet and to said first pair of links, and guide

rails within the cabinet and connected with the ironer unit for bodily rotating the ironer unit during its movement from one position to the other.

5. In a structure of the class described, the combination of a cabinet having an opening in a vertical wall thereof, an ironing unit adapted to be moved into and out of the cabinet through said opening, said unit being arranged to occupy a vertical position within the cabinet and a horizontal position outside of the cabinet, a pair of links pivotally connected to the ironer and having a sliding connection with the cabinet, a second pair of links pivotally connected to the cabinet and to said first pair of links, guide rails within the cabinet and connected with the ironer unit for bodily rotating the ironer unit during its movement from one position to the other, a supporting leg for the ironer in its horizontal position outside of the cabinet, and means for folding said leg into substantially parallel relation with the ironer unit as said unit is moved into the cabinet.

6. In a structure of the class described, the combination of a cabinet having a door opening in one of its vertical walls, an ironing machine unit adapted to occupy a vertical position within the cabinet or a horizontal position exteriorly of the cabinet, said ironing machine including a base member, a pair of curved guide rails within the cabinet and means connecting one end of the ironing machine base with said guide rails to bring about the bodily rotation of the ironing machine during its movement from one position to the other, vertical guide rails within the cabinet, link members pivotally connected to the ironing machine base at one end and having a sliding connection with said vertical guide rails at their other ends, and other links pivotally connected to said first mentioned links and to the cabinet.

7. In a structure of the class described, the combination of a cabinet having a door opening in one of its vertical walls, an ironing machine unit adapted to occupy a vertical position within the cabinet or a horizontal position exteriorly of the cabinet, said ironing machine including a base member, a pair of curved guide rails within the cabinet and means connecting one end of the ironing machine base with said guide rails to bring about the bodily rotation of the ironing machine during its movement from one position to the other, vertical guide rails within the cabinet, link members pivotally connected to the ironing machine base at one end and having a sliding connection with said vertical guide rails at their other ends, other links pivotally connected to said first mentioned links and to the cabinet, a folding leg for supporting the ironing machine in its horizontal position outside of said cabinet, said leg being mounted on the base of the ironing machine, and means for automatically folding and unfolding said leg during movement of the ironing machine into and out of the cabinet.

8. In a structure of the class described, the combination of a cabinet and an ironer unit, including a roll and a baseboard member, adapted to occupy a vertical position within the cabinet or a horizontal position outside of the cabinet, link members pivotally connected to the cabinet and to said base member and forming a pivotal axis about which the ironer unit rotates in the movement of said unit from one position to the other, curved guide rails within the cab-

inet, means pivotally connecting one end of the ironer unit with said guide rails, a hinged leg carried by said baseboard member for supporting the ironer unit in its horizontal position outside of the cabinet, and means for automatically swinging the leg into substantially parallel relation to the baseboard member as the ironer unit moves into vertical position in the cabinet.

9. In a structure of the class described, the combination of a cabinet having a door opening in one of its vertical walls and an ironer unit, including a baseboard member, an ironing roll and an ironing shoe movable through said opening to an upright position within the cabinet or to a horizontal position substantially outside of the cabinet, vertical guide members mounted in the cabinet adjacent the opening, a pair of links pivotally and slidingly connected to the said guide members at one end and at their other end pivotally connecting with the baseboard of the ironer unit substantially midway of the length of the unit, said latter pivotal connections providing an axis about which the ironer unit is rotated in the movement of said unit from one position to the other, a second pair of links pivotally connected to the cabinet and to the first pair of links, curved guide rails within the cabinet, means connecting one end of the ironing unit with said curved rails for supporting the ironer unit in its horizontal position and for guiding said end of the ironer unit from one position to the other, a foldable leg carried by said ironer unit at an appreciable distance from the supported end thereof for supporting the ironer unit in its horizontal position, and means for automatically folding and unfolding the leg as the ironer unit is moved from one position to the other.

10. In a structure of the class described, the combination of a cabinet having a door opening in one of its vertical walls and an ironer unit, including a baseboard member, an ironing roll and an ironing shoe movable through said opening to an upright position within the cabinet or to a horizontal position substantially outside of the cabinet, vertical guide members mounted in the cabinet adjacent the opening, a pair of links pivotally and slidingly connected to the said guide members at one end and at their other end pivotally connecting with the baseboard of the ironer unit substantially midway of the length of the unit, said lateral pivotal connections providing an axis about which the ironer unit is rotated from one position to the other, a second pair of links pivotally connected to the cabinet and to the first pair of links, curved guide rails within the cabinet, means connecting one end of the ironing unit with said curved rails for supporting the ironer unit in its horizontal position and for guiding said end of the ironer unit from one position to the other, a foldable leg carried by said ironer unit at an appreciable distance from the supported end thereof for supporting the ironer unit in its horizontal position, and means including a swingable bail member within the cabinet adapted to fold the leg as the ironer unit is moved into upright position within the cabinet.

11. In a structure of the class described, the combination of a cabinet, an elongated ironer unit adapted to occupy a vertical position within the cabinet or a horizontal operating position outside of the cabinet, means connected with the cabinet and the ironer unit for supporting and guiding the unit as it is moved from one

position to the other, an outboard supporting leg carried by the ironer unit, said leg being hinged to said unit and adapted to be swung into folded relation to the unit as the unit is moved into the cabinet, spring means normally urging the leg into supporting position, and a spring actuated bail for folding the leg as the unit is moved into the cabinet.

12. In a structure of the class described, the combination of a cabinet, an elongated ironer unit adapted to occupy a vertical position within the cabinet or a horizontal operating position outside of the cabinet, means connected with the cabinet and the ironer unit for supporting and guiding the unit as it is moved from one position to the other, an outboard supporting leg carried by the ironer unit, said leg being hinged to said unit and adapted to be swung into folded relation to the unit as the unit is moved into the cabinet, spring means normally urging the leg into supporting position, a spring actuated bail for folding the leg as the unit is moved into the cabinet, and locking means for locking the leg in its supporting position.

13. In a structure of the class described, the combination of a cabinet, an elongated ironer unit adapted to occupy a vertical position within the cabinet or a horizontal operating position outside of the cabinet, means connected with the cabinet and the ironer unit for supporting and guiding the unit as it is moved from one position to the other, an outboard supporting leg carried by the ironer unit, said leg being hinged to the ironer unit and swingable into folded relation, a cam, means connecting said cam to and movable by said supporting and guiding means, and means actuated by said cam to swing the leg into folded relation as the unit is moved into the cabinet.

14. In a structure of the class described, the combination of a cabinet, an elongated ironer unit adapted to occupy a vertical position within the cabinet or a horizontal operating position outside of the cabinet, means connected with the cabinet and the ironer unit for supporting and guiding the unit as it is moved from one position to the other, an outboard supporting leg carried by the ironer unit, said leg being hinged to the ironer unit and adapted to swing into folded relation thereto, gear means connected to and actuated by said ironer supporting mechanism, a rack member operatively associated with said gear and pivotally connected to the hinged leg for swinging the leg to folded or supporting position as the unit is moved from one position to the other.

15. In a structure of the class described, the combination of a cabinet, an ironer unit adapted to occupy a vertical position within the cabinet and a horizontal position outside of the cabinet, means for supporting the ironer unit and guiding it from one position to another, a folding leg for supporting said ironer in its horizontal position, means for folding the leg, a locking device for folding the leg in its supporting position, and a safety device for locking the leg in supporting position in the event of interference with the operation of the leg.

16. In a structure of the class described, the combination with a cabinet, of an elongated ironer unit arranged to occupy a vertical position within said cabinet or a horizontal operating position exteriorly of said cabinet; and means associated with said cabinet and ironer unit for supporting and guiding said unit in its

- movements into and out of said cabinet including link members, pivot means connecting the link members to said unit and about which pivot means said unit is rotatable, and means controlling the movements of said link members to guide said pivot means in a horizontal path. 5
17. In a structure of the class described, the combination with a cabinet; of an elongated ironer unit arranged to occupy a vertical position 10 within said cabinet or a horizontal operating position exteriorly of said cabinet; combined guide and supporting links for said ironer unit; pivot means connecting said links to the ironer unit and about which the latter is rotatable; 15 means controlling the movement of said links for guiding said pivot means in a horizontal path; and cooperating guide means on said cabinet and ironer unit, for guiding one end of said unit in its movements into and out of the 20 cabinet, and rotating said unit on said pivot means to swing said unit to vertical position when moved into said cabinet and to horizontal position when moved out of said cabinet. 25
18. In a structure of the class described, the combination with a cabinet; of an elongated ironer unit movable into and out of the cabinet; supporting guide links for said ironer unit; pivot means connecting said links to said unit, said unit being rotatable about said pivot means; 30 means on said cabinet for controlling the movements of said links for guiding said pivot means in a horizontal path; and cooperating means on said cabinet and unit for rotating the latter on said pivot means during movement of the 35 unit inwardly and outwardly of the cabinet. 40
19. In a structure of the class described, the combination with a cabinet; of an elongated ironer unit movable into and out of the cabinet; and supporting and guiding mechanism for said ironer unit connected with the cabinet and ironer unit for carrying the ironer unit into and out of the cabinet and rotating the unit to vertical position within the cabinet or to horizontal position outside of the cabinet, said supporting 45 and guiding mechanism including means for maintaining said ironer unit in horizontal position during the first part of its movement into the cabinet and during the last part of its movement out of the cabinet. 50
20. In a structure of the class described, the combination with a cabinet; of an elongated ironer unit adapted to occupy a horizontal position outside of said cabinet and to be moved into said cabinet for storage, said ironer unit including a base member; means for guiding said ironer unit for movement into and out of said cabinet; a folding leg for supporting the ironer unit in its horizontal position outside of the cabinet, said leg being mounted on the base of the ironer unit; and means position to be rendered operative when the center of gravity of 55 said ironer unit is disposed entirely within the limits of said cabinet for automatically folding and unfolding said leg during movement of said ironer unit into and out of the cabinet. 60
21. In a structure of the class described, the combination with a cabinet; of an elongated ironer unit adapted to occupy a vertical position within the cabinet or a horizontal position exteriorly of the cabinet, said ironer unit including a base member; means for guiding the ironer unit for movement into and out of the cabinet; a folding leg for supporting the ironer unit in its horizontal position outside of the cabinet, said leg being mounted on the base of the ironer unit 65
22. In a structure of the class described, the combination with a cabinet; of an elongated ironer unit adapted to occupy a vertical position within the cabinet or a horizontal position exteriorly of the cabinet, said ironer unit including a base member; means for guiding the ironer unit for movement into and out of the cabinet; a folding leg for supporting the ironer unit in its horizontal position outside of the cabinet, said leg being mounted on the base of the ironer unit 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

an upwardly direction toward the top of the cabinet during movement of said unit into the cabinet, and causing bodily reverse movement of said unit as it is withdrawn from the cabinet.

5 26. In a structure of the class described, the combination with an upright cabinet; of an elongated ironer unit adapted to occupy a vertical position within the cabinet between the top and bottom ends of the latter or a horizontal 10 position exteriorly of the cabinet; pivot means supporting the inner end of said ironer unit with respect to said cabinet; means carried by said cabinet for guiding the pivotal axis of said pivot means inwardly and outwardly of said cabinet 15 and toward and away from the upper end of the cabinet during movement of said unit inwardly and outwardly of said cabinet; and controlling means operatively connecting said ironer unit and cabinet for swinging said unit on the pivotal 20 axis of said pivot means during said movement

of the ironer unit inwardly and outwardly of the cabinet.

27. In a structure of the class described, the combination with an upright cabinet; of an elongated ironer unit adapted to occupy a vertical position within the cabinet between the top and bottom ends of the latter or a horizontal operating position exteriorly of the cabinet; means connecting said unit and cabinet for guiding the same into and out of the cabinet, 5 rotating the same from one of said positions to the other and moving the same endwise toward and away from the upper end of the cabinet, including a supporting pivot member bodily guided in an arcuate path with respect to said 10 cabinet and pivotally suspending the inner end of said unit; and additional means reacting between said ironer unit and cabinet for swinging said unit on the pivotal axis of said member.

ALFRED J. SHUTE. 20
